SHUTTLE

Harry Augustus Billings, Hopedale, Mass., assignor to Draper Corporation, Hopedale, Mass., a corporation of Maine

Application June 19, 1940, Serial No. 341,334

6 Claims. (Cl. 139—221)

This invention pertains to loom shuttles and more particularly relates to the construction and mounting of the threading blocks of such shuttles.

5 Shuttles of the type to which my invention applies commonly include a shuttle body having a bobbin receiving cavity, a threading block receiving recess at one end of such cavity and means for holding the threading block in the 10 recess.

In the usual prior construction the threading block is snugly fitted into the recess with close contact between the abutting surfaces of the wood of the shuttle and the metal of the threading block to prevent the warp threads of the 15 shed and the running filling thread from being caught therebetween. In such constructions the threading block is held in the recess by a screw passing through the walls of the recess and the 20 threading block. I find that it is difficult to secure sufficiently close contact between the abutting surfaces of the shuttle wood and the metal threading block due to unevenness in the construction of such surfaces and to expansion or 25 contraction of the wood as the shuttle is continued in use. However, it is necessary that these surfaces be kept in close contact and if the surfaces move apart it is essential that they be readjusted into close contact to prevent the warp 30 threads of the shed and the running filling thread from being caught therebetween.

Accordingly it is the principal object of my invention to provide a loom shuttle comprising a shuttle body having a bobbin receiving cavity and a threading block receiving recess longitudinally aligned therewith, a threading block seated in the recess, means for adjusting the threading block in said recess whereby a close contact may be had between the abutting surfaces of the threading block and the shuttle body and a horizontal screw passing transversely through the shuttle body and the threading block for clamping the threading block and adjusting means in adjusted position.

45 The foregoing and other objects of the invention are accomplished in the construction illustrated on the accompanying drawing, of which:

Fig. 1 is a view in section taken on line 1—1 of Fig. 2;

50 Fig. 2 is a front view of one end of the shuttle;

Fig. 3 is a view in cross-section taken on line 3—3 of Fig. 2; and

Fig. 4 is a detail view in perspective showing the adjusting element.

55 The shuttle shown on the drawing comprises a shuttle body 1 of the usual size and shape having the usual cavity 2 therein for receiving a bobbin 3 which is adapted to carry the filling supply used in weaving. The bobbin supporting end of

the shuttle is of any suitable usual construction and is accordingly not shown or described.

The eye end of the shuttle is provided with a recess 4 formed in the shuttle wood for the reception of a threading block 5, and has a side delivery eye 6 shown (on Fig. 1) as extending through the side wall of the shuttle and through which the filling from the bobbin usually passes during the passage of the shuttle through the shed. The front wall of the shuttle adjacent the 10 outer end of recess 4 is cut away to form a slot leading into the side delivery eye. The sides of the slots are bevelled to form inclined surfaces 7 and 8.

The threading block is provided with a base 15 portion 9 having upwardly-extending side walls 10 and 11 through which extends the longitudinal thread passage 12. Thread tensioning means may be provided such as oppositely disposed tension plates 13, 13' which extend transversely of 20 the thread passage 12.

The top portion 14 of the side wall 11 of the threading block 5 is substantially of triangular form and downwardly curved to conform to the contour of the top and side portions of the shuttle wood, substantially as indicated on Fig. 2. The bottom inclined surface 15' of the curved portion 15 of the threading block is seated on the inclined surface 7 of the slot leading to the side delivery eye. When these surfaces are in proper 30 engagement the curved contiguous outer surfaces of the wood of the shuttle and the metal of the threading block offer a continuous unobstructed surface over which the warp threads of the shed and the running filling thread may readily pass. 35 The forward top portion of the part 14 of the threading block extends outwardly and rearwardly forming a horn 16.

It may be well to note here that in these 40 specifications and in the appended claims I employ such terms as "outwardly," "rearwardly" and "front" as though the shuttle was positioned in a loom. Thus the side containing the side delivery eye is the front side of the shuttle and on Fig. 1 of the drawing "rearwardly" is away 45 from the front wall toward the top of the sheet. By "outwardly" I mean in a direction longitudinally of the shuttle from the bobbin cavity toward the tip of the shuttle.

In prior constructions the threading block is 50 usually secured in the recess provided therefor by means of a screw passing through the side walls of the recess and the threading block. However, insofar as I am aware, no means have been provided for adjusting the threading block with- 55 in the recess.

Due to the unevenness of the contacting inclined surfaces of the shuttle body and the threading block it is difficult to secure close fitting contact between such surfaces unless some 60

means is provided to draw the threading block down tightly onto the wood of the shuttle body. Also as the shuttle continues in use the wood shrinks thereby leaving a slight opening between the inclined surfaces of the wood and metal. When such opening exists, the warp threads of the shed and the running filling thread are liable to be caught therein and broken.

In the drawing, I have shown the preferred embodiment of a construction providing means for adjusting the threading block within the recess. Such means may comprise an eccentric member 17 journalled in a hole 18 in the base 8 of the threading block 5. The member 17 may be formed as an extension of a bushing 19 journalled in the front wall of the recess 4. The eccentric 17 and bushing 19 have a longitudinal hole 20 extending therethrough. Member 17 is eccentric with relation to the hole 20. The hole 20 is of the proper size to loosely receive a screw 21. The screw 21 extends through the front wall of the recess 4, the bushing 19, the eccentric member 17 and is threaded into a nut 22 secured in a recess 23 in the rear wall of the recess 4.

The bushing 19 is positioned on the screw 21 with the end 24 of the bushing engaged by the head 25 of the screw, either directly or through the means of intervening washers 26, as may be desired. The bushing 19 may be provided with a shoulder 27 which extends around the screw 21 and bears against the front face of the threading block 5. The bushing 19 may also be provided with a screw driver slot 28 for convenience in turning the bushing. When the screw 21 is tightened, the bushing 19 is acted upon by the head of the screw to force the shoulder 27 against the threading block and thereby clamp the threading block and bushing together.

In the embodiment shown, if, due to unevenness of the inclined surfaces of the block or wood, or shrinkage of the wood, the inclined surface 15' of the threading block is raised from the inclined surface 1 of the opening leading to the side delivery eye, the screw 21 is removed (leaving the members 17, 19 in place) and the bushing is turned slightly to the right, as viewed on Fig. 2 by means of a screw driver engaged with slot 28. This turning of the bushing moves the threading block downwardly and the two surfaces 15' and 1 are again brought tightly into contact. Then, when the screw 21 is replaced it will firmly hold the bushing and threading block in adjusted position.

Having fully disclosed the preferred embodiment of my invention, I claim:

1. A loom shuttle comprising a shuttle body having a recess adjacent one end thereof, said recess having an inclined surface forming a seat, a threading block seated in said recess and having a corresponding inclined surface engaging said first named surface, adjustable means for moving said block whereby said engaging inclined surface of said block is brought into tight engagement with said engaging inclined surface of said recess and means for clamping said adjustable means in adjusted position.

2. A loom shuttle comprising a shuttle body having a recess therein, said recess having longitudinal side walls, one of said side walls being cut away forming an inclined surface, a threading block seated in said recess and having an inclined surface resting upon said first named inclined surface, adjustable means engaging said block for moving same whereby said contacting

inclined surfaces may be pressed tightly together and means for clamping said block and said adjusting means in adjusted position.

3. A loom shuttle comprising a shuttle body having a recess therein, said recess having longitudinal side walls, one of said side walls being cut away forming an inclined surface, a threading block seated in said recess and having an inclined surface resting upon said inclined surface of said side wall of said recess, an adjustable member journalled in one of said side walls and having an eccentric extension thereon, said extension being journalled in said block, whereby upon rotation of said member said block is moved bringing said inclined surface of said block into tight engagement with said inclined surface of said wall and means to clamp said block and said adjustable member in adjusted position.

4. A loom shuttle comprising a shuttle body having a recess adjacent one end thereof, a threading block seated in said recess, a screw member passing transversely through said shuttle body and said block for securing said block in said recess, a bushing mounted on said screw and having an eccentric extension thereon, said eccentric extension being journalled in said block, whereby upon rotating said bushing said block is adjusted, said bushing having a shoulder bearing against said block and an end engaged by the head of said screw to thereby clamp said block in its adjusted position in said recess when said screw is tightened.

5. A loom shuttle comprising a shuttle body having a recess therein, said recess having a front and rear wall, said front wall having an opening therein communicating with said recess and also having a slot leading to said opening, the side walls of said slot being bevelled forming inclined surfaces, a threading block seated in said recess, said threading block having an inclined surface in snug engagement with one of said first named inclined surfaces, means for securing said block in said recess, means for moving said block to bring said engaged inclined surfaces into closer contact and means carried by and actuated by said first named means for clamping said block and said second named means in said recess.

6. In a shuttle for an automatic replenishing loom, the combination of a shuttle body having a recess therein, said recess having a front and rear wall, said front wall having an opening therein communicating with said recess and also having a slot leading to said opening, the side walls of said slot being bevelled forming inclined surfaces, a threading block seated in said recess and having an inclined surface in snug engagement with one of said first named inclined surfaces, a screw member passing transversely through said front and rear walls of said recess and said threading block, a bushing mounted on said screw member and journalled in said front wall of said recess, said bushing having an eccentric extension thereon, said extension being journalled in said threading block, means provided on said bushing for rotating same whereby said threading block is movable to bring said engaged inclined surfaces of said block and said slot into closer engagement, said bushing having a shoulder bearing against said block and an end engaged by the head of said screw to thereby clamp said block in adjusted position upon tightening of said screw.

HARRY AUGUSTUS BILLINGS.
